UNITED STATES PATENT OFFICE.

BENJAMIN S. BENSON, OF BALTIMORE, MARYLAND.

IMPROVEMENT IN MACHINES FOR MOLDING PIPES.

Specification forming part of Letters Patent No. 116,141, dated June 20, 1871.

To all whom it may concern:

Be it known that I, BENJAMIN S. BENSON, of the city and county of Baltimore and State of Maryland, have invented certain new and useful Improvements in Machines for Molding Pipe; and I do hereby declare the following to be a full, clear, and exact description of the same, reference being had to the accompanying drawing making a part of this specification, in which—

Figure 1 represents a perspective view of the machine. Fig. 2 represents a vertical section through the same.

Similar letters of reference, where they occur in the separate figures, denote like parts of the machine in the drawing.

My invention consists, first, in the combination of a steady-shaft and sliding packer with a revolving flask, for the purpose of steadyng the packer while the flask is being rammed with molding-sand. My invention further consists in combining a feed-hopper and revolving measurer with a revolving flask, so that the sand shall be measured and regulated to quantity required in the flask. My invention further consists in combining with such parts of the molding-machine as require free movement one upon the other, and are liable to be clogged with dust that accompanies molding operations, pipes or tubes for conducting air through to blow out such dust or dirt.

To enable others skilled in the art to make and use my invention, I will proceed to describe the same with reference to the drawing.

A represents the base of the machine, and B the uprights for sustaining the operative parts of the molding-machine. C is a turn-table, supported on or in the base A, and revolved by means of an endless belt, *a a*, passing around a pulley at *b*. Upon this turn-table C the flask D is placed and secured, so as to turn with said table. The shaft *c* that carries the packer D' is tubular, and is fastened to a cross-head, E, that can move up and down on or against the uprights B, and be guided and relieved of undue friction thereon through friction-rolls *d*, bearing against the ways *e* on the uprights. A rope, cord, or chain, *f*, is fastened to the cross-head E and passes over a pulley, *g*, and to its lower end is attached a weight, *h*, which aids in raising the packer D',

as the sand is pressed and built up in the flask, underneath said packer, or its spiral flange *i*. The steady-shaft F I make tubular, for a purpose to be hereafter described. It is made to freely but snugly fit and pass through the packer-shaft *c*, and is supported above the top of the shaft *c*, should it pass above it, (which, however, is not absolutely necessary,) by the cross-piece G of the frame. The lower end of the steady-shaft F has a recess in it, which receives a journal or bearing, *j*, which is on the turn-table, and which keeps that end of said steady-shaft in true position; and said steady-shaft, in turn, keeps the packer and packer-shaft in exactly a true position with regard to the flask, so that the mold is perfectly true, there being no vibration or straining of the packer or its shaft out of true working position. H is a permanent table, through which the upper part of the turn-table C revolves, and friction-rolls 2 2 are interposed between the stationary and the turning tables, to avoid undue friction. To blow out the dust which would accumulate and prevent the free movement of the friction-rolls, an air-tube is introduced, as at *k*, through which air may be blown to remove such dust; and, for a similar purpose, an air-tube, *l*, is inserted in the tubular steady-shaft F, through which air may be blown, which finds its way through openings, as at 3 3 3, &c., and blows out any dust or dirt that may get into the packer-shaft *c*, and which, if allowed to accumulate, would prevent the free movement of the steady-shaft through the packer-shaft, or vice versa. To the top of the steady-shaft F is attached a rope or chain, *m*, which passes over a pulley, *n*, and thence to a drum, *o*, which is turned by a crank, *p*, so as to raise up said shaft when necessary. A rope or chain, *q*, is also attached to one of the weights *h*, which extends to the drum *r*, by which the packer-shaft and packer may also be raised up when necessary to do so. I is a hopper, into which the sand used in packing the flask is put. In this hopper there is a float or measuring-wheel, *J*, with buckets *s* therein, which takes the sand in measured quantities out of the hopper and delivers it into the chute *K*, whence it runs into the top of the flask D; and that the measuring-wheel and the flask may rotate with exactness and uniformity of

speed, when regulated, the same endless belt or band *a a* that turns the measuring-wheel also turns the flask, and thus they run together or stop together, as the case may be. The packer, with its shaft, is some one hundred pounds heavier than its balances or weights *h*, so that the sand is very firmly packed by the packer in the flask.

Having thus fully described my invention, what I claim, therein as new, and desire to secure by Letters Patent, is—

1. In combination with the revolving flask *D*, the sliding packer *D'*, packer-shaft *c*, and the steady-shaft *F*, as and for the purpose described and represented.

2. In combination with a revolving flask and sliding packer, the hopper, measuring-wheel, and conveyer, when timed and regulated to run together and deliver to the flask measured quantities of sand, as and for the purpose described.

3. The air-tubes *k l*, arranged in connection with the friction-rolls *2*, and the shafts *F c*, as and for the purpose described and represented.

BENJ. S. BENSON.
